UNITED STATES PATENT OFFICE.

ALBERT E. MAYNARD, OF SOUTHBRIIDGE, MASSACHUSETTS, ASSIGNOR TO AMERICAN OPTICAL COMPANY, OF SOUTHBRIIDGE, MASSACHUSETTS, A VOLUNTARY ASSOCIATION OF MASSACHUSETTS.

LENS-HOLDER.

1,191,905.

Specification of Letters Patent. Patented July 18, 1916.

Application filed June 11, 1914. Serial No. 844,572.

To all whom it may concern:

Be it known that I, ALBERT E. MAYNARD, a citizen of the United States, residing at Southbridge, in the county of Worcester and State of Massachusetts, have invented 5 certain new and useful Improvements in Lens-Holders, of which the following is a specification.

My invention relates to improvements in 10 lens holders, and has particular reference to an improved holder for use in properly positioning lenses within an edging machine or the like.

The leading object of my invention is the 15 provision of a simple and efficient holder which may be readily secured in position to hold one or a plurality of lenses, as may prove desirable.

A further object of my invention is the 20 provision of an improved holder which shall embody means for putting an additional spring tension grip on the lenses after the holder has been brought into correct gripping engagement therewith.

Other objects and advantages of my improved lens holder should be readily apparent from the following description taken 25 in connection with the accompanying drawings, and it will be understood that I may 30 make any modifications in the specific details of construction shown and described within the scope of the appended claims without departing from or exceeding the spirit of my invention.

Figure I represents a perspective view of 35 my improved holder. Fig. II represents a longitudinal sectional view showing the parts in released position. Fig. III represents a similar view showing the parts 40 locked in engagement with the lens.

In the drawings, in which similar characters of reference are employed to denote corresponding parts throughout the several views, the numeral 1 designates the main 45 or base member of my device having the furcated jaw portion 2 provided with the upstanding pin 3 adapted to fit into the apertures in the clamp pad 5 for securing the said pad in correct position upon the jaw. 50 It will be understood that the furcations of

these jaws are such as to span the clamp spindle of an edging machine and lock the pad in correct position relative thereto when the spindle and the pad may be inter-engaged and the lenses clamped in position in 55 the machine, and my instrument withdrawn. Hinged to the opposite end of the main member 1 from that at which the jaws 2 are located is the plate 6 carrying the spring metal clamping member 7 which has the pair 60 of spaced jaws 8 with depending pins 9 for clampingly engaging a lens or lenses and securing the same in position against the clamping head pad, as is clearly illustrated in Fig. III. A spring 10 or the like, may 65 be interposed between the members 1 and 7 to normally resiliently hold the same apart.

To secure the members 1 and 7 in desired adjusted position relative to each other I employ my improved locking means. 70 Mounted as in the slot 11 of the member 1 is the post 12, having a pin portion 13 at the lower end engaged by the blade spring 14 which normally swings the post outwardly, as clearly illustrated in Fig. II. 75 Said post has the serrated or toothed inner edge 15. It will be understood, however, that while I have illustrated this as toothed or serrated that I may use a threaded post or the like should the same appear preferable. The plate 6 terminates in an enlargement or head 16, which is split by a flap 17, through which the upper portion of the post 12 extends, a serrated or toothed jaw portion 18 being disposed at the end of the slot, 80 this jaw portion being formed either integral with or separate from the head 16, as may be desired. It will thus be seen that the spring 14 normally holds the post and jaw members 16 out of engagement with 85 each other, while bringing of the parts into engagement will cause interlocking of the teeth and thus lock the members 1 and 7 against any relative movement. To attain this locking of these parts in correct position I journal in the head 16 the pin 19 which may be in the form of an eccentric or may have the flat face 20 as illustrated. This flat face is normally in engagement 90 with the post 12, but rotation of the pin 19 95 100

through the medium of the handle 21 serves to move the flat face out of engagement with the post, thus camming or forcing the post to swing rearwardly against the tension 5 of the spring 14 and bringing the toothed portion 15 and 16 into interlocking engagement. In performing this operation the lens is preferably placed in position on the member 5 and first a downward pressure 10 applied to the handle 21 until the lens and member 5 are correctly gripped between the members 1 and 7, the handle then being pressed either rearwardly or forwardly to lock the parts in dis-adjusted position. If 15 desired, however, to slightly increase the swinging tension gripping of the lens within spaced limits, I may make use of the eccentric or cam members 22, which are mounted on the pin 19 and rotate therewith. In 20 the use of these members movement of the handle 21 serves to rotate the pin 20 and first to swing the post into locked position, continued movement causing the cam member 22 to bear down upon and swing down- 25 wardly the member 7 and thus to add an additional spring tension to the initial gripping pressure of the device against the lenses being held on the pad.

From the foregoing description taken in 30 connection with the accompanying drawings, the construction and operation of my improved lens holder should be readily apparent, and it will be seen that I have provided a simple and efficient device in which a pressure on the operating handle serves to force 35 the two lens holding members into correct engagement with the lens located therebetween, while forward or rearward pressure on the handle will then serve to lock the 40 parts in desired adjusted position. It will be further noted that in the particular form here illustrated this forward or rearward pressure on the handle serves not only to lock the parts but also to increase the spring 45 tension gripping action of my device to further eliminate the possibility of the lenses slipping, as might occur were not this additional tension placed thereon.

I claim:

50 1. In a device of the character described, the combination with a base member having a downwardly offset furcated clamping head at one end and having a depending rest near the other end for holding the handle 55 portion of the device in raised position, of a supplemental rigid member pivotally secured to the handle end of the base member and terminating in a downwardly opening hook, a resilient clamp jaw secured to 60 the second pivoted member near its point of pivotance and free therefrom adjacent the hook portion, a shaft journaled in the bight of the hook and having a cam member for engaging and forcing inward the spring

clamp relative to the second pivoted mem- 65 ber, a post carried by the base member and adapted for interlocking engagement with the second pivoted member, and means on the shaft for securing the post in said interlocking relation upon actuation of the 70 cam, substantially as and for the purpose described.

2. A lens holder, comprising a pair of pivotally connected members, provided with clamping jaws, a post pivoted to one of the 75 members and projecting through the other, said post having a serrated portion and the other member having a serrated jaw adapt- 80 ed to engage the serrations of the post, and a manually operable double cam member 85 having a portion for forcing and securing the serrations of the post and jaw in interlocking relation and having a second portion for forcing the jaws into tight engagement with each other after they have been secured in adjusted position through the me- 90 dium of the post and serrated jaw.

3. The combination with a pair of pivoted members, one of said members having clamping jaws, of a resilient clamping mem- 95 ber carried by the other of said two first named members, means for locking the two first named members in desired relatively adjusted position, and additional means for swinging the resilient clamping member in- 100 ward after the two pivoted parts have been secured in desired adjusted relation.

4. In a lens holder, the combination with a pair of pivoted members, of a resilient 105 gripping member carried by one of said members, means carried by the other pivoted member and extending through the resilient gripping member and the other pivoted member for locking the parts in adjusted position, resilient means for holding the 110 locking device normally in an operative position, means for shifting the locking device into operative position, and additional means operated upon movement of the locking means into operative position for exerting additional pressure against the resilient gripping member, substantially as described.

5. A device of the character described, in- 115 cluding a main jaw member, a frame mem- 120 ber pivoted to the jaw member, a resilient gripping member carried by the frame mem- 125 ber, a post pivoted to the main jaw member and extending upwardly through the re- sili- 130 ent gripping member and the frame member, said post having a serrated face, a serrated jaw carried by the frame mem- 135 ber, means for normally swinging the post to hold its serrations out of engagement with those of the jaw member, a cam device for limiting the swinging movement of the post, a second cam operatively inter-related with the first mentioned cam member, and means for simultaneously operating said cam mem-

ber, whereby the first cam member serves to force the post serrations in interlocking engagement with those of the jaw to secure the two pivoted members in desired adjusted relation, while the second cam member serves to spring the resilient gripping member inward into operative position.

In testimony whereof I affix my signature in presence of two witnesses.

ALBERT E. MAYNARD.
